ROSARY RING

Delio R. Canela 'D., East Elmhurst, N.Y.

Application October 21, 1957, Serial No. 48,191

Term of patent 7 years

(Cl. D45—10)

Fig. 1 is a front elevational view of a rosary ring, or similar article showing my new design the details of the cross portion being omitted.

Fig. 2 is a rear elevational view thereof, the details of the cross portion being omitted.

Fig. 3 is a left side elevational view thereof.

Fig. 4 is an enlarged/fragmentary front elevational view thereof, showing the details of the cross portion; and

Fig. 5 is an enlarged fragmentary rear elevational view thereof, showing the details of the cross portion of the rosary ring shown in Fig. 2, showing a portion of the features of the new design in greater detail.

The dominant features of my design reside in the portion shown in full lines.

I claim:

The ornamental design for a rosary ring, or similar article, substantially as shown, and described.
